[57] **CLAIM**

The ornamental design for the male plug housing having a circuit breaker, as shown and described.

DESCRIPTION

FIG. 1 is a top perspective view of a male plug housing having a circuit breaker;
FIG. 2 is a top view of the housing of FIG. 1;
FIG. 3 is a rear view of the housing of FIG. 1;
FIG. 4 is a left side view thereof, the right side view thereof being a mirror image;
FIG. 5 is a front view of the housing of FIG. 1; and,
FIG. 6 is a bottom view of the housing of FIG. 1.
The broken line showing throughout the drawing figures is included for the purpose of illustrating environmental structure only and forms no part of the claimed design.
